UNITED STATES PATENT OFFICE.

GEORGE WESP, OF NEW YORK, N. Y., ASSIGNOR TO ROSENTHAL CHINA CORPORATION,
OF NEW YORK, N. Y., A CORPORATION OF NEW YORK.

DESIGN FOR A PLATE OR SIMILAR ARTICLE.

Application filed August 10, 1927. Serial No. 23,039. Term of patent 7 years.

To all whom it may concern:

Be it known that I, GEORGE WESP, a citizen of Germany, and resident of the borough of Manhattan, city, county, and State of New York, have invented a new, original, and ornamental Design for a Plate or Similar Article, of which the following is a specification, reference being had to the accompanying drawing, forming part hereof,

which drawing is a face view of a plate or similar article, illustrating my new design, the dot-and-dash-lined segment indicating that the design therein is to be repeated around the rim of the plate.

I claim:

The ornamental design for a plate or similar article, as shown, and described.

GEORGE WESP.
